UNITED STATES PATENT OFFICE.

ARTHUR C. ROBBINS, OF OAKLAND, CALIFORNIA.

DESIGN FOR A COUPLING FOR BATTERY-PLATES.

SPECIFICATION forming part of Design No. 27,694, dated September 28, 1897.

Application filed June 2, 1896. Serial No. 594,047. Term of patent 8½ years.

To all whom it may concern:

Be it known that I, ARTHUR C. ROBBINS, a citizen of the United States, residing in the city of Oakland, county of Alameda, and State of California, have invented and produced a new and original Design for a Coupler for Battery-Plates, of which the following is a specification, reference being had to the accompanying drawings, showing the same.

10 The leading features of my design consist in a flat and relatively narrow strip or ribbon of pliable metal, such as lead, with a cylindrical block at each end pierced with a central hole or aperture that extends axially through it. These two blocks form the terminals of the flat strip or ribbon, and the flat strip or ribbon is normally in a plane coinciding with the axis of the block, but is sometimes bent out of a straight line into a bow or 15 curve, according to the distance between the two cells or elements that are to be united

electrically by this coupler. The form and arrangement of these parts will be understood from the drawings, wherein—

A indicates the strip or ribbon, B B the cylindrical block, and B^X B^X the apertures in such blocks for the pins or studs on the battery-plates. 25

Figure 1 of said drawings is a view of the design in plan, and Fig. 2 is a side view, 30 these two views being considered necessary to fully illustrate the form of my said design.

What I claim is—
The design for a coupler for battery-plates herein shown and described. 35

In testimony that I claim the foregoing I have hereunto set my hand and seal.

ARTHUR C. ROBBINS. [L. S.]
